UNITED STATES PATENT OFFICE

114,199

DESIGN FOR A DISPLAY ARTICLE HOLDER

Frederick W. Rettenmeyer, Meriden, Conn., assignor to The Napier Company, Meriden, Conn., a corporation of Connecticut

Application December 29, 1938, Serial No. 82,046

Term of patent 7 years

To all whom it may concern:

Be it known that I, Frederick W. Rettenmeyer, a citizen of the United States, residing at Meriden, in the county of New Haven and State of Connecticut, have invented a new, original, and ornamental Design for a Display Article Holder, of which the following is a specification, reference being had to the accompanying drawing, forming part thereof.

Fig. 1 is a perspective view of a display article holder showing my new design; and

Fig. 2 is a top plan view of the same.

I claim:

The ornamental design for a display article holder, substantially as shown.

FREDERICK W. RETTENMEYER.
